UNITED STATES PATENT OFFICE.

JAMES J. VLCEK, OF RAVENNA, NEBRASKA.

BABY-CARRIAGE ROCKING AND ROLLING MECHANISM.

Application filed December 17, 1925. Serial No. 76,135.

This invention relates to new and useful improvements in baby carriage rocking and rolling mechanism.

The primary object of the invention is to provide a power driven mechanism by means of which the basket or body of a baby carriage may be rocked from side to side and the entire carriage rolled over its supporting surface alternately in a forward and 10 then in a backward direction.

A further object of the invention is to provide speed and distance controls for the rolling portion of the mechanism.

Other objects and advantages of the invention will be apparent during the course 15 of the following description.

In the accompanying drawings forming a part of this specification and in which like numerals are employed to designate like 20 parts throughout the same,

Figure 1 is a vertical sectional view of the mechanism embodying this invention with the body or basket of the carriage shown in dotted lines,

25 Figure 2 is a top plan view, partly broken away, of the mechanism and chassis portion of the device embodying this invention,

Figure 3 is a rear elevational view, partly broken away, of the mechanism embodying 30 this invention,

Figure 4 is a front elevational view of the front spring support for the carriage body or basket,

Figure 5 is a fragmentary elevational 35 view showing a modified form of connection between the power plant and the ground engaging wheels for producing a rolling movement of the carriage,

Figure 6 is a detail top plan view of a 40 portion of the rocking and rolling mechanism,

Figure 7 is a bottom plan view of the structure shown in Fig. 6.

Figure 8 is a vertical sectional view taken 45 upon line VIII—VIII of Fig. 6,

Figure 9 is a vertical sectional view taken upon line IX—IX of Fig. 6,

Figure 10 is a fragmentary side elevational 50 view of the structure shown in Figs. 6 and 7,

Figure 11 is a detail perspective view of the front support for the carriage basket or body and shows in detail the members employed for directly producing the rock-

ing movement of the said basket or body, 55 and

Figure 12 is a detail perspective view of the rear spring support for the carriage basket or body.

In the drawings, wherein for the purpose 60 of illustration is shown a preferred embodiment of this invention, the numeral 5 designates the rear axle of the carriage which is permanently connected to the side spring members 6 which are curved upwardly and inwardly at their opposite ends 7 for having fastened to their extremities the transversely extending carriage basket or body supporting bars 8. The front axle 9 is also 65 permanently fastened to these spring members 6, as clearly illustrated. Rotatably mounted upon the free ends of the axles 5 and 9 are the ground engaging wheels 10 and 11.

The basket or body 12 of the carriage 70 has suitably secured to its underface the transversely extending bars 13 which have the depending ears 14 located intermediate their ends and to which the intermediate portions of the transverse supporting bars 8 are pivotally connected, as at 15. The bars 8 and 13 are provided with shock absorbing bumpers 16, as best illustrated in 75 Figs. 3, 4, 11 and 12.

80 Mounted above the front axle 9 and connected thereto by the brackets 17 is a combination platform and gear casing 18 which has mounted thereupon the motor 19. This motor is preferably of the spring actuated type, although any other desired form of 85 motor may be employed. The motor shaft 20 has mounted upon its outer end the pinion 21 which meshes with a gear 22 permanently keyed or fastened to a transversely extending shaft 23. This shaft 23 will be termed 90 the driven shaft as it is permanently connected to the motor shaft 20 and rotates constantly when the motor 19 is operated.

The outer end of this driven shaft 23 is 95 suitably journaled in a bearing member 24 and has permanently fixed thereto a bevel gear 25 which constantly meshes with a bevel gear 26 connected to the longitudinally extending shaft 27 which is journaled in the 100 bearings 28 supported by the combination platform and gear casing 18.

105 The free end of this shaft 27 has permanently fixed thereto a pinion 29 which

meshes with a gear 30 carried by the shaft 31. This gear 30 is clearly illustrated in Figs. 3 and 11 as having eccentrically and pivotally connected thereto, as at 32, the 5 crank rods 33 which have their outer ends pivotally connected to the bell crank levers 34 which are pivoted intermediate their ends, as at 35, in the cutout portions 36 of the front basket or body supporting bar 8. The upper ends of the bell crank levers 34 have journaled thereon the rollers 37 which are intended to be placed in engagement with the underface of the front bar 13, secured to the front end portion of the carriage body or basket 12, for causing the said basket or body to rock upon its pivots 15.

It will now be seen that when the motor 19 is operating, the longitudinally extending shaft 27 will rotate for causing the gear 30 to rotate. This rotary movement of the gear 30 will pivot the bell crank levers 34 in opposite directions for causing their roller carrying ends 37 to alternately engage the underface of the basket or body carrying bar 13 for rocking said basket or body.

The means employed for rolling the entire carriage alternately in forward and rearward directions includes a compound ring gear structure 38 which is housed within the 39 combination platform and gear casing 18 and is mounted upon the vertical shaft 39 carried by the bearings 24. This compound gear member 38 has formed on its upper face two concentric ring gears 40 and 41. 40 Adjustable upon the driven shaft 23 is a pinion 42 which is operated by the shift lever 43 which has an inverted T-shaped support 44 that rides in a guide 45. This pinion 42 may be located in two operative positions for causing the compound member 38 to rotate at different speeds. One of these positions is in connection with the key 46 carried by the driven shaft 23 and in which position the pinion 42 will mesh with the outer ring gear 41 of the member 38. The 45 second operative position is with the pinion 42 connected to the driven shaft 23 by the key 47, carried by the latter, in which position the pinion 42 will mesh with the inner ring gear 40. It will now be seen that a 50 change speed connection is provided between the driven shaft 23 and the member 38 and that the locating of the pinion 42 intermediate the ring gears 40 and 41 will permit the member 38 to stand idle while the driven shaft 23 continued to rotate.

60 Journaled beneath the combination platform and gear casing 18 and above the front axle 9 is a transversely extending shaft 48 which has its outer ends, see Figs. 1 and 3, provided with bevel pinions 49 which constantly mesh with the bevel ring gears 50 65 permanently fastened to the forward ground engaging wheels 11. In Fig. 5, the transverse shaft 48 is illustrated as having mount-

ed upon its end a pinion 49^a which meshes with the gear 50^a. Figure 5 merely illustrates a modified form of connection between the shaft 48 and a front wheel 11.

Figure 7 clearly illustrates the bottom face of the member 38 as having formed thereon the concentric, segmental gears 51 and 52. The shaft 48, on opposite sides of the bearing 24, is provided with the pairs of spaced keys 53 and the reciprocating or loosely mounted pinions 54. These pinions are actuated by the shift levers 55 which are carried by T-shaped supports 56 slidably positioned in the guides 57. By operating the levers 55, the pinions 54 may be moved into either of their two operative positions. When the pinions 54 are arranged in one operative position they will be connected to the transverse shaft 58 by the inner keys 58 and will be located for registering with the inner segmental gear 51 when the same travels around its axis. It will now be seen that with the pinions 54 in this one operative position, the shaft 48 will be rotated in one direction when the segmental gear 51 engages one pinion 54 and will rotate in the opposite direction when the ring gear 51 meshes with the remaining pinion 54. The second operative position for these pinions 54 is when they are connected to the shaft 48 by the outer keys 53. This second operative position will also cause the shaft 48 to alternately rotate in opposite directions, but at a different speed and for a different length of time.

It will now be seen that the motor 19 may be connected to the compound member 38 by the pinion 42 for causing the member 38 to rotate at two different speeds. This rotating member may be connected to the shaft 48 for causing the latter to rotate in opposite directions for brief periods and the changing of the location of the pinions 54 will vary the speed and length of rotation of the shaft 48.

It is to be understood that the forms of this invention herewith shown and described as to be taken as preferred examples of the same, and that various changes in the shape, size, and arrangement of parts may be resorted to without departing from the spirit of the invention or the scope of the subjoined claims.

Having thus described the invention, I claim:

1. In a device of the type described, the combination with a wheeled carriage having a pivotally supported body, of a power plant carried by the body, a driven shaft constantly connected to the power plant, a second shaft operatively connected to the driven shaft, a gear driven by the second shaft, a pair of crank rods eccentrically connected at the same point to the gear, means for operatively connecting the crank rods

to the carriage body for rocking the latter upon its pivot support, and means operated by the driven shaft for rolling the carriage on its supporting surface alternately in opposite directions.

2. In a device of the type described, the combination with a wheeled carriage including a pivotally supported body, of a power plant carried by the carriage, a rotatable gear, means for connecting the gear to the driven shaft, a pair of oppositely extending crank rods eccentrically, pivotally connected to the gear at the same point, a bell crank lever pivotally connected to the outer end of each crank rod, a pivot support for each bell crank lever to arrange its free end in operative relation with the carriage body for rocking the latter upon its pivot support, and means operated by the power plant for rolling the carriage on its supporting surface alternately in opposite directions.

3. In a device of the type described, the combination with a wheeled carriage having a pivotally supported body, of a power plant carried by the carriage, a driven shaft constantly connected to the power plant, an eccentric connection including a bell crank between the driven shaft and body for rocking the body on its pivotal support, a shaft extending transversely of the carriage, connections between the opposite ends of the transverse shaft and the front wheels of the carriage for rotating the wheels when the transverse shaft is rotated, and means for connecting the driven shaft with the transverse shaft for causing the latter shaft to rotate alternately in opposite directions.

4. In a device of the type described, the combination with a wheeled carriage having a pivotally supported body, of a power plant carried by the carriage, a driven shaft con-

stantly connected to the power plant, a gear carried by the driven shaft, a pair of crank rods eccentrically connected to the gear to operate in opposite directions, lever devices for operatively connecting the crank rods to the carriage body for rocking the latter upon its pivot support, a transversely extending shaft connected at its outer ends to the wheels of the carriage for rotating said wheels when the transverse shaft is rotated, and means for connecting the driven shaft to the transverse shaft for causing the latter to rotate alternately in opposite directions.

5. In a device of the type described, the combination with a wheeled carriage having a pivotally supported body, of a power plant carried by the carriage, a driven shaft constantly connected to the power plant, a rotatably supported member, means for rotating said member, a pair of oppositely extending crank rods eccentrically, pivotally connected to the rotating member, a bell crank lever operatively connected to the free end of each crank rod, pivot supports for the bell crank levers for arranging their free ends to engage the opposite sides of the carriage body for rocking the latter on its pivot support, a shaft extending transversely of the carriage, a connection between the free ends of the shaft and the front wheels of the carriage for causing said wheels to rotate when the transverse shaft is rotated, means for connecting the transverse shaft to the driven shaft for causing the transverse shaft to rotate in opposite directions, and means for varying the speed of rotation of the transverse shaft.

In testimony whereof I affix my signature.

JAMES J. VLCEK.
